INVENTOR.

UNITED STATES PATENT OFFICE

97,369

DESIGN FOR A TEXTILE FABRIC

Eugene Irving Hanson, New York, N. Y.

Application July 29, 1935, Serial No. 57,851

Term of patent 3½ years

To whom it may concern:

Be it known that I, Eugene Irving Hanson, a citizen of the United States of America, residing in the Borough of Manhattan, city, county, and State of New York, have invented a new, original, and ornamental Design for a Textile Fabric, of which the following is a specification, reference being had to the accompanying drawing, forming part thereof, wherein,

The figure is a plan view view of a textile fabric showing my new design.

I claim:

The ornamental design for a textile fabric substantially as shown.

E. IRVING HANSON.
